CONTROL OF FUEL FEEDING DEVICES

Albert E. Baak, Minneapolis, Minn., assignor to
 Minneapolis-Honeywell Regulator Company,
 Minneapolis, Minn., a corporation of Delaware

Application January 2, 1941, Serial No. 372,784

19 Claims. (Cl. 200—33)

This invention is concerned with the control of fuel feeding devices, principally stokers, and is particularly directed to improvements in automatic systems for controlling stokers in response to temperature and time and to improvements in timing apparatus adapted for use in such systems.

It is common practice to control stokers by means of a space thermostat and a timing device, the latter serving to intermittently operate the stoker for fire maintaining purposes during mild weather. The control arrangement is usually electrical, comprising circuits controlled by contact mechanism operated by the timing device and by the space thermostat.

The object of my invention is to provide an improved electrical system for controlling a stoker by a thermostat and a timer, the improvements residing in part in arrangements whereby control from the timer and adjustments of the timed operation are simplified so as to reduce the cost of manufacture and enable operators to adjust the control with greater facility.

Another object is to provide a timing device embodying a fixed cam and a rotatable cam follower carried by the ratchet wheel of a pawl and ratchet mechanism operated by an electric motor, the mechanism being so constructed as to cause the ratchet wheel to move the cam follower at a proper speed to produce the desired timing.

Another object is to provide a timing device embodying a cam having alternate dwells and depressions with improved adjustable means for blanking out one or more depressions to vary the relative number of dwells and depressions.

Another object is to provide a timing unit embodying a relatively fixed cam and a rotatable cam follower carried on a wheel adapted to be reciprocated in the direction of its axis.

Another object is to provide a timing unit embodying relative flat cam members with a cam follower carried on a rotatable element located relatively close to the cam members and lying in the same plane so that the parts occupy a minimum of space.

Another object is to provide an adjustable cam having gaps in its periphery forming depressions between adjacent dwells with manually adjustable elements movable into positions for blanking out certain of the gaps to vary the relative number of dwells and depressions.

Numerous other objects and advantages of my invention will become apparent from the following detailed description wherein:

Figure 1 is a diagrammatic view of a stoker system embodying my invention.

Figure 2 is an exploded isometric view of certain detail parts of the timing mechanism.

Figure 3 is a plan view of the panel carrying the timing mechanism.

Referring to Figure 1 of the drawing, numeral 10 designates an automatic stoker of any well known type which forms part of a heating system not shown which may be any of various well known types of systems. My invention is primarily concerned with the mechanism for controlling the stoker which mechanism includes a space thermostat 11 which is of a known type. 15 The thermostat 11 comprises a circular bimetal element 12 having one end fixed and carrying two flexible switch blades 13 and 14 at its other end. The blades 13 and 14 cooperate with fixed electrical contacts 15 and 16 respectively. The 20 thermostat 11 is so arranged that upon a fall in temperature the blades 13 and 14 are moved to the left, and at a predetermined temperature which may be 72° for example, blade 13 engages the contact 15. Blade 14 engages contact 16 at a predetermined lower temperature which may be one or two degrees lower for example, such that this temperature may be 70°. The operation of this thermostat will be referred to again more particularly hereinafter.

25 The thermostat controls a relay 20 comprising a winding 21 having an armature attached to switch blades 22 and 23, the blades 22 and 23 cooperating with fixed electrical contacts 24 and 25 respectively. When the winding 21 is energized, the armature is attracted so as to move the switch blades into engagement with their respective contacts. Power for operation of the relay is supplied by a stepdown transformer 27 comprising a primary winding 28 and a secondary winding 29, the primary winding having a greater number of turns than the secondary winding. Numerals 30 and 31 designate line conductors connected to a suitable source of power not shown. Numeral 32 designates a manual switch comprising a switch arm 33 which is normally in engagement with a fixed electrical contact 34. Connected in series with the manual switch 32, as shown, is a fuse 35. The primary winding 28 of transformer 27 is normally connected across line conductors 30 and 31 by a circuit extending from line conductor 30 through wire 36, fuse 35, manual switch 32, wire 37, primary winding 28 and wire 38 to line conductor 31.

30 The relay 20 is also controlled by a timing

35

40

45

50

55

mechanism which forms the principal substance of my invention and which is generally designated by the numeral 40. The timing mechanism includes an electric timing motor which may be a well known Telechron motor and which is designated by the numeral 41. The motor 41 includes an armature 42 mounted on a shaft 43 and a winding 44. The winding 44 is connected across the line conductors 38 and 39 by a circuit extending from line conductor 38 through a wire 45, winding 44 and wire 46 to line conductor 39. Numeral 47 designates a casing which encloses a gear reduction train which forms a part of the Telechron motor, and extending from the casing 47 is a shaft 48 which is driven through the gear reduction train at a speed of one revolution per minute. On the end of shaft 48 is a cam 49 having a gradually rising contour with a single dropoff. The cam 49 has a cam follower 50 riding thereon, and the cam follower is carried on the left end of a lever 51 pivoted on a fixed member 51A. Pivoted to the right end of lever 51 is a small lever 52 forming a pawl cooperating with a ratchet wheel 53. Referring to Figure 2, numeral 54 designates a small coil spring attached to the lower end of pawl 52 and normally urging the pawl in a clockwise direction against the teeth of the ratchet wheel 53. The ratchet wheel 53 is mounted on a shaft 55 which is journaled in a panel 56 and on the end of which is carried a manual rotating knob 57.

The cam follower 50 is below the cam 49 as seen on Figure 1. As the cam 49 is rotated, the cam follower 50 is gradually moved downwardly, as seen on Figure 1, that is to rotate the lever 51 in a counter-clockwise direction, looking at Figure 2, so as to move the pawl 52 upwardly and thereby rotate the ratchet wheel 53 in a clockwise direction as seen on Figure 2. When the cam follower 50 drops off the single dropoff on cam 49, the coil spring 54 acting on the pawl 52 rotates the lever 51 in a clockwise direction keeping the cam follower 50 in engagement with the cam 49 and bringing the pawl 52 into engagement with the next lower tooth on the ratchet wheel 53. As the cam 49 rotates, the ratchet wheel 53 is thus moved in a clockwise direction one tooth at a time. The ratchet wheel 53 has 60 teeth so that it is rotated at a speed of one revolution per hour, pawl 52 being actuated once a minute.

The ratchet wheel 53 lies in a plane parallel to that of panel 56, and between the ratchet wheel and the panel 56 are a number of circular members, the structure of which may best be seen in Figure 2, wherein these members are shown spaced apart and isometrically. A plan view of the panel 56 is shown in Figure 3.

The ratchet wheel 53 also has a hub 60 extending downwardly, as seen in Figure 1. The hub 60 carries an insulating member 61 at its end which bears against a screw 62 carried at the midpoint of a contact bracket 63 made of spring material. The bracket 63 is fixed at its left end and at its right end it carries electrical contacts 64 and 65. The contact 64 cooperates with contact 66 carried on a contact bracket 67, and the contact 65 cooperates with a contact 68 carried on a contact bracket 69. The bracket 63 is arranged so as to normally tend to spring upwardly so as to cause the screw 62 to urge the hub 60 and the ratchet wheel 53 upwardly as seen on Figure 1. However, normally with the relay deenergized as in Figure 1, the parts are in the positions shown in that figure with

the bracket 63 in a position having the contacts 64 and 65 in engagement.

Referring now more particularly to the circular members disposed between the ratchet wheel and the panel 56, numeral 73 (see Figure 2) designates a flat ring-shaped cam member. The shaft 55 is centrally disposed as respects the member 73, and this member is held against the panel 56 by brackets 74 and 75. The engagement of the brackets 74 and 75 with the edge of member 73 is free enough to permit the member 73 to be rotated while it remains in the same relative position as respects the shaft 55; that is, it remains in a position with the shaft 55 centrally disposed as respects the member 73. The member 73 has a pin 76 extending perpendicularly to the plane of its surface and through an arcuate slot 77 in the panel 56 (see Figures 2 and 3). Adjacent the slot 77 are graduations bearing numerals from 1 to 7, the purpose of which will be referred to more particularly hereinafter. Around the inner edge of the member 73 are arcuate openings or gaps 80, 81, 82 and 83 which are equally spaced angularly. As will presently appear, the portions of member 73 between the gaps form cam dwells with the gaps forming depressions between the dwells.

Numeral 84 designates a circular member having the same diameter as the inner diameter of the ring member 73. The member 84 has a central aperture 85 through which the shaft 55 passes, the member 84 not being fastened to the shaft but being non-rotatably fastened to panel 56. The member 84 is disposed within the ring member 73, these members having the same thickness and lying in the same plane and both being flush with the surface of one side of panel 56 when the parts are in assembled relationship. The member 84 has three cut-out portions 88, 89 and 90 which form gaps in its periphery. These cut-out portions are equally spaced angularly, being 90° apart, and they all have the same shape as best seen in Figure 2. Each of these openings has straight sides near the periphery of member 84, and the sides then taper inwardly toward the center of the member 84, the tapering portions connecting with rectilinear portions which form guide-ways as will presently be described. The guide-ways are designated by the numerals 91, 92 and 93 respectively. The member 84 has another cut-out portion 94 forming a gap in its periphery, this cut-out portion being spaced 90° from the cut-out portions 88 and 89 but having a different shape. The lower part of the cut-out portion 94 has the shape of an arcuate slot 95 as seen on Figure 2. Normally the gaps in the periphery of member 84 lie adjacent the gaps in the ring member 73, and the amount of overlap of adjacent gaps may be varied by rotating the ring member 73. This may be done by grasping pin 76 and moving it in the slot 77 in panel 56. The pin 76 may be set adjacent any of the graduations adjacent slot 77. As the pin 76 is moved toward a higher number adjacent to the slot, the ring member 73 is moved in a counter-clockwise direction as seen on Figure 2, so as to increase the amount of overlap of adjacent gaps. The purpose of this will be referred to more particularly hereinafter.

The member 84 also has three small apertures 97, 98 and 99 which are arranged along an arc relatively near to the center of member 84 and apertures are relatively closely spaced

angularly. The purpose of these apertures will be described presently.

Disposed in the openings 88, 89 and 90 are movable elements 102, 103 and 104 respectively. These elements have the same shape as their respective openings so as to fit into the openings, but the broader portion of each of the elements does not have quite the same radial extent as the broader portion of the openings. Each of the elements has a narrow stem-like portion which fits into the guide-ways previously described. The elements 102, 103 and 104 are slideable radially in their respective openings and the elements may be moved outward radially until their outer edges are flush with the inner edge of the ring member 73. The elements 102 and 104 are shown in this position in Figure 2. The outer edges of the elements, as is obvious, are arcuate, the arc having the same radius as the member 84. From the foregoing it is apparent that when the elements 102, 103 and 104 are moved outward radially, they blank out the gaps in the periphery of member 84, and when these elements are moved inward radially to the position in which element 103 is shown, the gaps in the periphery of member 84 are again made effective. The portions of member 84 between the gaps act as cam dwells, the same as do the portions of member 73 between its gaps as will presently become apparent. The elements 102, 103 and 104 have the same thickness as member 84 and of course lie in the same plane as member 84.

Each of the elements 102, 103 and 104 has a small pin extending perpendicularly to its surface in a direction away from the panel 56. These pins are designated by the numerals 106, 107 and 108 on Figure 2.

Numerical 109 designates a disk made of relatively thin spring material having a central opening 110 through which the shaft 55 passes. The disk 109 has three slots in it designated by the numerals 111, 112 and 113. When the parts are in assembled relationship, the disk 109 is flush with the member 84, as may be seen in Figure 1, with the pins 106, 107 and 108 extending through the slots 111, 112 and 113 respectively. The disk 109 has also a pin 115 extending perpendicularly to its surface through the arcuate slot 95 in member 84 and through an arcuate slot 116 in the panel 56. The slot 116 has graduations adjacent it numbered 15, 30 and 60 as shown. By grasping the pin 115 and moving it in slot 116, the disk 109 can be rotated, for purposes which will presently be described. Each of the slots 111, 112 and 113 has an arcuate portion as shown, the center of the arc in each case being at the center of the disk. Each of the slots 111 and 113 also has a straight portion which slants from the midpoint of the slot toward the center of the disk. The slot 112 has a straight portion which slants from the midpoint of the slot away from the center of the disk.

The disk 109 has a generally arcuate slot 129, the center of which is spaced from the center of the disk. The portion of the material enclosed by the slot 129 has a small boss 121 formed therein, the boss protruding slightly from the surface of the disk on the side adjacent member 84. The boss 121 cooperates with the three apertures 97, 98 and 99 in member 84, the arrangement being such that the boss may fit into any one of the apertures. When the parts are in assembled relationship with the pin 115 opposite the graduation marked 30 of slot 116, the

disk 109 is in a position with boss 121 engaged in aperture 98 and with the pins 106, 107 and 108 at the midpoints of their respective slots in disk 109. Under these circumstances the elements 102, 103 and 104 are in the position shown in Figure 2. Thus member 84 has only two effective gaps, as will appear later. The timing mechanism with the parts in this position will produce two timed operations of the stoker per hour.

If the pin 115 should now be moved to the right end of slot 116 opposite the graduation marked 15, the disk 109 will be rotated in a counter-clockwise direction, as seen on Figure 2, the boss 121 being moved out of aperture 98 and to the left into aperture 97. The material enclosed within the slot 129 of disk 109 is flexed outwardly, that is, away from member 84, when the disk 109 is rotated, the boss 121 acting as a cam bearing against the material at the periphery of the aperture which the boss is in at the beginning of the rotation of the disk 109. Thus when the disk 109 is rotated, the material enclosed by slot 129 is flexed slightly out of the plane of the disk. The boss 121 acts as a detent to hold the disk 109 securely in any one of its three positions.

When the pin 115 is thus moved to the right end of slot 116, thereby rotating the disk 109 in a counter-clockwise direction as seen on Figure 2, the pins 106 and 108 move to the ends of the straight portions of their respective slots. The pin 107 moves to the end of the arcuate portion of its respective slot. During the operation as just described, it will be understood that the disk moves and that the pins extending through the slots 111 and 113 also move. The straight portions of the slots 111 and 113 act in the manner of a cam to force their respective pins radially toward the center of member 84, thereby moving the elements 102 and 104 into positions corresponding to the position in which element 103 is shown in Figure 2. Rotation of disk 109 in a counter-clockwise direction does not cause pin 107 to move, because the slot 112 of disk 109 is merely moved from a position at which the pin 107 is at the midpoint of the slot 112 to a position wherein the pin 107 is at the end of the arcuate portion of the slot 112. Obviously, counter-clockwise movement of disk 109, as just described, does not require movement of pin 107 and consequently element 103 remains in the position shown in Figure 2. Thus, with the pin 115 at the right end of slot 116, all of the gaps in the periphery of member 104 are made effective and under these circumstances, as will presently appear, the timing mechanism causes the stoker to operate every fifteen minutes. The numerals adjacent the slot 116 designate minutes of time. When the pin 115 is at the midpoint of slot 116, as shown in Figure 3, the parts are in the positions shown in Figure 2, with the pins 106, 107 and 108 at the midpoints of their respective slots in the disk 109. Under these circumstances two of the gaps at the periphery of member 84 are effective and, as will presently appear, the time mechanism will cause an operation of the stoker every thirty minutes.

When the pin 115 is moved to the left end of slot 116 adjacent the graduation marked 60, the disk 109 is rotated in a clockwise direction as seen on Figure 2, the boss 121 moving from aperture 98 to aperture 99 so as to hold the disk in its third position. When the disk 109 is so rotated, the arcuate portions of slots 111 and 113 move relatively to pins 106 and 108, this move-

ment of the disk 109 not requiring movement of the pins 106 and 108 so that the elements 102 and 104 remain in the positions in which they are shown in Figure 2. However, when disk 109 is thus rotated clockwise, pin 107 moves in the straight portion of its respective slot to the end of the slot, the slot acting in the manner of a cam to force the pin 107 radially away from the center of member 84. This moves element 103 to a position corresponding to the positions in which elements 102 and 104 are shown in Figure 2. Thus, when the pin 107 is at the left end of slot 116, only gap 84 of member 84 is effective, and under these circumstances, as will presently appear, the time mechanism produces an operation of the stoker once every sixty minutes.

The ratchet wheel 83 has member 120 attached thereto, the bracket member 120 being formed from a relatively narrow strip of material shaped substantially into the form of a square. Two of the corners of the square are secured to the ratchet wheel 83 by rivets or the like, as may be seen best in Figure 1. Another corner of bracket member 120 is bent outwardly somewhat from the ratchet wheel 83, and this corner has a projecting finger comprising an angular portion 121 and a portion 122 parallel to the plane of the ratchet wheel. The portions 121 and 122 form a cam follower disposed at a radial distance from the center of the ratchet wheel so as to bear against adjacent portions of cam members 73 and 84 as the ratchet wheel is rotated. The cam follower is visible on Figure 2 through a rectangular opening 123 in the ratchet wheel 83. Bracket member 120 is normally urged against the cam members 73 and 84, by the upward force exerted by bracket 63. The cam follower member 122, as pointed out above, bears against both cam members 73 and 84, and its width or radial extent is such that whenever the cam follower is at a point in its rotation where adjacent gaps in the cam members 73 and 84 overlap, the cam member will drop in against the panel 86 (it being remembered that the cam members 73 and 84 are flush with the panel member), that is, the bracket member 63 will move the ratchet wheel upwardly, as seen in Figure 1, with a relatively quick or snap movement whenever the cam follower 122 is at a point where adjacent gaps in the cam members 73 and 84 overlap. This movement of the ratchet wheel and bracket member 63 will move normally closed contacts 85 and 86 out of engagement and will move contacts 84 and 88 into engagement with a relatively quick or snap action.

As seen on Figure 2, member 73 is normally adjusted so that its gaps extend beyond the gaps in member 84 a certain amount in a clockwise direction. Thus after the cam follower 122 has dropped into adjacent gaps where they overlap, the cam follower will be lifted again, that is moved downwardly looking at Figure 1, when it reaches the clockwise extremity of the gap in member 84. For instance, if the cam follower 122 dropped into the adjacent gaps 86 and 84, the cam follower will be moved back to its normal position when it engages the shoulder, forming the clockwise extremity of gap 84. The cam follower will not be raised suddenly out of the gaps, but its angular portion 121 will engage the shoulder at the extremity of the gap in member 84 and this angular portion will cause the cam follower to be more or less gradually cammed out of the gaps thereby moving the ratchet wheel 83 outwardly, that is downwardly looking at Figure 75

1, relatively slowly. Consequently, as ratchet wheel 83 is thus moved, the bracket 63 will be moved downwardly, looking at Figure 1, relatively slowly so as to disengage contacts 84 and 88 and to bring contacts 85 and 86 into engagement, the latter contacts being engaged a brief period of time after contacts 84 and 88 disengage. The purpose of this manner of operation of the contacts will presently become apparent.

Referring now to the operation of my system as a whole, the relay 28 may be energized by the thermostat 11 whenever there is a demand for heating in the space where the thermostat is located. When the temperature in the space drops to 70°, blades 13 and 14 engage their respective contacts completing a circuit for relay 28 as follows: from secondary 28 of transformer 27 through wire 130, contact 15, blade 13, element 12, blade 14, contact 16, wire 131, wire 132, winding 21 and wire 133 back to secondary 28. Energization of winding 21 moves blades 22 and 23 of the relay into engagement with their respective contacts. Engagement of contact 26 and blade 23 completes a maintaining circuit for the relay which is independent of contact 16, this circuit being as follows: from secondary 28 of the transformer through wire 130, contact 15, blade 13, element 12, wire 134, blade 23, contact 25, wire 135, bracket 63, contacts 85 and 86, bracket 63, wire 132, winding 21 and wire 133 back to secondary 28. Inasmuch as this circuit is independent of contact 16, it is apparent that after the relay has been energized, it will not be deenergized until the space temperature rises to 72°, at which temperature, blade 13 disengages contact 15. Whenever the relay is energized bringing contacts 22 and 24 into engagement, the stoker is operated through the following circuit: from line conductor 30 through wire 36, fuse 35, manual switch 32, wire 37, wire 136, blade 22, contact 24, wire 138, the stoker and wire 139 to line conductor 31.

When the weather is relatively mild, and there are infrequent demands for stoker operation made by the thermostat, it is necessary that the stoker be intermittently operated for brief periods to prevent the fire from going out. My timing mechanism provides such a function. Thus, whenever the cam follower 122, which is of course constantly rotated, drops into adjacent gaps of the cam members 73 and 84, contacts 84 and 88 are brought into engagement in the manner above described. This completes a circuit for the relay as follows: from secondary 29 through wire 130, wire 140, bracket 67, contacts 86 and 84, bracket 63, wire 132, winding 21 and wire 133 back to secondary 28. Completion of this circuit energizes the relay and the stoker is operated in the same manner as described above. The stoker continues operating until the cam follower is raised by the shoulder at the clockwise extremity of the gap in member 84 as described above. When this occurs, contacts 84 and 88 are brought into engagement for a brief lay and contacts 85 and 86 are again brought into engagement. As explained above, contacts 85 and 88 are brought into engagement for a brief period of time after contacts 84 and 86 are disengaged. The purpose of this is as follows. It may happen that during the time the relay is energized by the timing mechanism, blade 13 of the thermostat may be brought into engagement with contact 15. This position of the thermostat is not one demanding stoker operation, but it is one wherein the thermostatic maintaining circuit

of the relay may be completed. Thus, at the expiration of the timed fire maintaining period, if contacts 65 and 68 were brought into engagement before or at the same time that contacts 64 and 66 disengage, the above described maintaining circuit for the relay which extends through blade 13 and contact 15 of the thermostat would be completed before the relay had an opportunity to be deenergized so as to disengage blade 23 from contact 25. Therefore, the operation is such that when contacts 64 and 66 disengage, relay 20 becomes deenergized before contacts 65 and 68 are engaged.

As previously pointed out, the ratchet wheel 53 is rotated at a speed of one revolution per hour. The number of minutes that the stoker is operated during a timed operation is of course dependent upon the length of time that the cam follower 122 is in one of the depressions formed by overlapping adjacent gaps in the members 73 and 84. When the pin 76 is moved to the left end of slot 77 (Figure 3) adjacent the graduation marked 1, (this would mean movement of pin 76 to the right in Figure 2) adjacent gaps in the members 73 and 84 are brought into registry with each other. The angular extent of the gaps is such that under these circumstances the timed operations of the stoker are of seven minutes duration as indicated by the numeral adjacent the slot 77. As the pin 76 is moved to the right end in slot 77, as seen on Figure 3, the amount of overlap of adjacent gaps is reduced, and consequently the length of timed operations of the stoker is correspondingly reduced to a number of minutes determined by the number adjacent slot 77 at which the pin 76 is positioned.

Under different operating conditions and with different types of fuel, it is sometimes desirable to provide for different programs of fire maintaining operation. That is, under some circumstances it may be desirable to operate the stoker once an hour for a predetermined number of minutes, or it may be desirable to operate the stoker twice or four times an hour for the same number of minutes or for a different number of minutes. To provide for various programs, that is, to provide for varying the number of timed operations during one cycle lasting a given period of time, I have provided the adjustment comprising the pin 115 in slot 116. As described above, this adjustment varies the number of effective gaps in the cam member 84. Whenever a gap in the cam member 84 is blanked out to render it ineffective in the manner already described, the corresponding adjacent gap in the member 73 is of course also rendered ineffective. When the pin 115 is at the midpoint of slot 116, two of the gaps in member 84 are effective and two are ineffective as already described. Under these circumstances, there will be two timed operations of the stoker every hour, it being remembered that the ratchet wheel 53 makes one revolution per hour, or in other words, there will be a timed operation of the stoker every thirty minutes. If it is desired that there be only one timed operation per hour, the pin 115 is moved to the left end of slot 116. Under these circumstances, all of the gaps of cam member 84, as described above, are made ineffective except the gap 94 and consequently there is only one timed operation of the stoker per hour or per revolution of the ratchet wheel 53. If it is desired that there be a timed operation of the stoker every fifteen minutes, the pin 115 is moved to the right end of slot 116. Under these circumstances all of

the gaps in the periphery of cam 84 are made effective as described above, and inasmuch as there are four gaps, there will now be four timed operations of the stoker per revolution of ratchet wheel 53, that is per hour, or in other words, there will be a timed operation of the stoker every fifteen minutes.

From the foregoing it will be apparent to those skilled in the art that I have provided a timing arrangement having manifold advantages, it being of a very simple but effective nature. The arrangement provides simple means of adjusting the length and number of operating periods utilizing very small and inexpensive parts. Most of the elements comprising the timing mechanism are flat and are disposed in parallel planes lying very close to each other or in the same plane, so that the timing unit as a whole has an extremely small depth, and its largest dimensions need be but little greater than the diameter of the ratchet wheel. Obviously, the nature of the construction and arrangement of parts is such that the entire unit can be made to occupy a minimum of space even though the construction is such that the action is positive and the use of delicate parts or the use of parts subject to rapid deterioration is avoided.

The embodiment of my invention which I have disclosed is representative of its preferred form although there are modifications and variations which may be made by those skilled in the art. My invention is not to be limited by my disclosure which is illustrative, but its spirit and scope is to be determined only in accordance with the appended claims.

I claim as my invention:

1. In a timing device, in combination, means comprising a relatively flat circular cam member having circularly arranged, spaced dwells and depressions between the dwells, means forming a flat ring-shaped member surrounding said first member with the flat faces of said ring shaped member and said first member in substantially the same plane, said ring-shaped member having portions forming alternate dwells and depressions along its inner edge, the latter dwells and depressions being adjacent corresponding dwells and depressions in the first member, said members being relatively adjustable to vary the amount of overlap of said corresponding dwells and depressions, a cam follower member adapted to ride on both said members so as to drop into the depressions in the members where the adjacent depressions overlap, the effective length of the dwells and depressions as respects actuation of the cam follower member depending upon the relative adjustment of the cam members, adjustable means associated with one of said members comprising an element adapted to bridge adjacent dwells of said one member whereby to blank out the depressions therebetween, and means for moving said element radially as respects the circularly arranged dwells and depressions into the path of said cam follower whereby the number of effective cam dwells is varied.

2. In a timing device, in combination, means comprising a relatively flat circular cam member having circularly arranged, spaced dwells and depressions between the dwells, means forming a flat ring-shaped member surrounding said first member with the flat faces of said ring shaped member and said first member in substantially the same plane, said ring-shaped member having portions forming alternate dwells and depressions along its inner edge, the latter dwells

and depressions being adjacent corresponding dwells and depressions in the first member, said members being relatively adjustable to vary the amount of overlap of said corresponding dwells and depressions, and a cam follower member adapted to ride on both said members so as to drop into the depressions in the members where the adjacent depressions overlap, the effective length of the dwells and depressions as respects actuation of the cam follower member depending upon the relative adjustment of the cam members, adjustable means associated with one of said members comprising an element adapted to bridge adjacent dwells of said one member whereby to blank out the depressions therebetween, and means for moving said element radially as respects the circularly arranged dwells and depressions into the path of said cam follower whereby the number of effective cam dwells is varied, said last means comprising a rotatable disk having a slot therein, said element having a pin engaged in said slot, the slot being so shaped and positioned that as the disk is rotated, the pin is constrained to move in the slot in a manner to move the element radially.

3. In a timing device, in combination, means comprising a relatively flat circular cam member having circularly arranged, spaced dwells and depressions between the dwells, means forming a flat ring-shaped member surrounding said first member with the flat faces of said ring shaped member and said first member in the same plane, said ring-shaped member having portions forming alternate dwells and depressions along its inner edge, the latter dwells and depressions being adjacent corresponding dwells and depressions in the first member, said members being relatively adjustable to vary the amount of overlap of said corresponding dwells and depressions, and a cam follower member adapted to ride on both said members so as to drop into the depressions in the members where the adjacent depressions overlap, the effective length of the dwells and depressions as respects actuation of the cam follower member depending upon the relative adjustment of the cam members, adjustable means associated with said first member comprising an element adapted to bridge adjacent dwells of said first member whereby to blank out the depressions therebetween, means for moving said element radially as respects the circularly arranged dwells and depressions into the path of said cam follower whereby the number of effective cam dwells is varied, said last means comprising a manually adjustable plate having a slot therein, said element having a pin engaged in said slot, the slot being so shaped and positioned that as the plate is moved the pin is constrained to move in the slot in a manner to move the element radially.

4. In combination; a cam disk assembly and a cam follower disk; means for mounting said cam follower disk and said cam disk assembly in parallel planes for relative rotation about a common axis; and means for causing relative rotation of said cam follower disk and said disk assembly about said common axis; said cam disk assembly comprising a substantially flat circular cam disk having alternately arranged dwells and depressions along its periphery, and a substantially flat second cam member having a circular opening substantially corresponding in diameter to the external diameter of said circular cam disk, said second cam member being mounted surrounding said circular cam disk with the faces

5 of said cam members in a common plane, said second cam member having alternately arranged dwells and depressions along the edge of said circular opening, said circular cam member and said second member being rotatably adjustable with respect to each other to vary the amount of overlap of the dwells and depressions of the respective members; and said cam follower disk having a cam follower portion projecting axially into engagement with said cam disk assembly, said cam follower portion engaging both the outer portion of said circular cam member and the inner portion of said second cam member so as to drop into the depressions in said cam members only where said depressions overlap.

5. In combination; a cam disk assembly and a cam follower disk; means for mounting said cam follower disk and said cam disk assembly in parallel planes for relative rotation about a common axis; and means for causing relative rotation of said cam follower disk and said disk assembly about said common axis; said cam disk assembly comprising a substantially flat circular cam disk having alternately arranged dwells and depressions along its periphery, and a substantially flat second cam member having a circular opening substantially corresponding in diameter to the external diameter of said circular cam disk, said second cam member being mounted surrounding said circular cam disk with the faces of said cam members in a common plane, said second cam member having alternately arranged dwells and depressions along the edge of said circular opening, said circular cam member and said second member being rotatably adjustable with respect to each other to vary the amount of overlap of the dwells and depressions of the respective members, said circular cam disk having blanking members associated with certain of said depressions and adapted to be moved to a position in which they blank out said depressions; and said cam follower disk having a cam follower portion projecting axially into engagement with said cam disk assembly, said cam follower portion engaging both the outer portion of said circular cam member and the inner portion of said second cam member so as to drop into the depressions in said cam members only where said depressions overlap.

6. In combination; a cam disk assembly and a cam follower disk; means for mounting said cam follower disk and said cam disk assembly in parallel planes for relative rotation about a common axis; and means for causing relative rotation of said cam follower disk and said disk assembly about said common axis; said cam disk assembly comprising a substantially flat circular cam disk having alternately arranged dwells and depressions along its periphery, and a substantially flat second cam member having a circular opening substantially corresponding in diameter to the external diameter of said circular cam disk, said second cam member being mounted surrounding said circular cam disk with the faces of said cam members in a common plane, said second cam member having alternately arranged dwells and depressions along the edge of said circular opening, said circular cam member and said second member being rotatably adjustable with respect to each other to vary the amount of overlap of the dwells and depressions of the respective members, said circular cam disk having blanking members associated with certain of said depressions and adapted to be moved to a

position in which they blank out said depressions; and means comprising a further disk rotatable about said axis for selectively moving one or more of said blanking members into blanking position; and said cam follower disk having a cam follower portion projecting axially into engagement with said cam disk assembly, said cam follower portion engaging both the outer portion of said circular cam member and the inner portion of said second cam member so as to drop into the depressions in said cam members only where said depressions overlap.

7. In combination; a cam disk assembly and a cam follower disk; a control panel; means for mounting said cam follower disk and said cam disk assembly parallel to said panel for relative rotation of said cam follower disk and cam disk assembly about a common axis; and means for causing relative rotation of said cam follower disk and said disk assembly about said common axis; said cam disk assembly comprising a substantially flat circular cam disk having alternately arranged dwells and depressions along its periphery, a substantially flat second cam member having a circular opening substantially corresponding in diameter to the external diameter of said circular cam disk, said second cam member being mounted surrounding said circular cam disk with the faces of said cam members in a common plane, said second cam member having alternately arranged dwells and depressions along the edge of said circular opening, said circular cam member and said second member being rotatably adjustable with respect to each other to vary the amount of overlap of the dwells and depressions of the respective members, and a knob secured to one of said cam members and projecting through an arcuate slot in said control panel for rotatably adjusting said members with respect to each other; and said cam follower disk having a cam follower portion projecting axially into engagement with said cam disk assembly, said cam follower portion engaging both the outer portion of said circular cam member and the inner portion of said second cam member so as to drop into the depressions in said cam members only where said depressions overlap.

8. In combination; a cam disk assembly and a cam follower disk; a control panel; means for mounting said cam follower disk and said cam disk assembly parallel to said panel for relative rotation of said cam follower disk and cam disk assembly about a common axis; and means for causing relative rotation of said cam follower disk and said disk assembly about said common axis; said cam disk assembly comprising a circular cam disk having alternately arranged dwells and depressions along its periphery, a second cam member having a circular opening substantially corresponding in diameter to the external diameter of said circular cam disk, said second cam member being mounted surrounding said circular cam disk with the faces of said cam members in a common plane, said second cam member having alternately arranged dwells and depressions along the edge of said circular opening, said circular cam member and said second member being rotatably adjustable with respect to each other to vary the amount of overlap of the dwells and depressions of the respective members; a knob secured to one of said cam members and projecting through an arcuate slot in said control panel for rotatably adjusting said members with respect to each other; said circu-

lar cam disk having blanking members associated with certain of said depressions and adapted to be moved to a position in which they blank out said depressions; and means comprising a further knob operatively connected to said blanking members and projecting through a further arcuate slot in said control panel for selectively moving one or more of said blanking members into blanking position; and said cam follower disk having a cam follower portion projecting axially into engagement with said cam disk assembly, said cam follower portion engaging both the outer portion of said circular cam member and the inner portion of said second cam member so as to drop into the depressions in said cam members only where said depressions overlap.

9. In combination; a cam disk assembly and a cam follower disk; a control panel; means for mounting said cam follower disk and said cam disk assembly parallel to said panel for relative rotation of said cam follower disk and cam disk assembly about a common axis; and means for causing relative rotation of said cam follower disk and said disk assembly about said common axis; said cam disk assembly comprising a substantially flat circular cam disk having alternately arranged dwells and depressions along its periphery, and a substantially flat second cam member having a circular opening substantially corresponding in diameter to the external diameter of said circular cam disk, said second cam member being mounted surrounding said circular cam disk with the faces of said cam members in a common plane, said second cam member having alternately arranged dwells and depressions on its face along the edge of said circular opening, said circular cam member and said second member being rotatably adjustable with respect to each other to vary the amount of overlap of the dwells and depressions of the respective members, said circular cam disk having blanking members associated with certain of said depressions and adapted to be moved to a position in which they blank out said depressions; means comprising a further disk rotatable about said axis for selectively moving one or more of said blanking members into blanking position; and a knob secured to said disk and projecting through an arcuate slot in said panel for rotatably adjusting said disk and hence varying the position of said blanking members; and said cam follower disk having a cam follower portion projecting axially into engagement with said cam disk assembly, said cam follower portion engaging both the outer portion of said circular cam member and the inner portion of said second cam member so as to drop into the depressions in said cam members only where said depressions overlap.

10. In combination; a cam disk and a cam follower; means for causing relative rotation of said cam follower and cam disk; said cam disk having alternately arranged annular dwells and depressions forming a circular cam track on the face of said disk with the center of said circular track on said axis, said cam disk having slots connecting with certain of said depressions, said slots extending radially inwardly with respect to the center of said circular track, and blanking members disposed in said slots with their outer faces flush with the outer face of the cam disk, said blanking members being radially slideable in said slots into and out of said depressions so as to either fill said depressions flush with the face of said cam or to leave said depressions open; a further disk disposed adjacent said cam disk

and revolvable about said axis; and means operatively connecting said further disk and said blanking members and effective upon said further disk being rotated to shift various ones of said blanking members into said depressions.

11. In combination; a cam disk and a cam follower disk; means for mounting said cam disk and cam follower disk in parallel planes for relative rotation about a common axis; said disks being axially movable with respect to each other and being biased towards each other; means for causing relative rotation of said cam follower disk and cam disk about said common axis; said cam disk having alternately arranged annular dwells and depressions forming a circular cam track on the face of said disk with the center of said circular track on said axis, said cam disk having slots connecting with certain of said depressions, said slots extending radially inwardly with respect to the center of said circular track, and blanking members disposed in said slots with their outer faces flush with the outer face of the cam disk, said blanking members being radially slidable in said slots into and out of said depressions so as to either fill said depressions flush with the face of said cam or to leave said depressions open; a further disk disposed adjacent said cam disk and revolvable about said axis; and means operatively connecting said further disk and said blanking members and effective upon said further disk being rotated to shift various ones of said blanking members into said depressions; and said cam follower having a cam follower portion projecting axially into engagement with said cam disk so as to cause said disks to periodically move apart axially against their bias.

12. In a time switch; a cam disk and a cam follower disk; means for mounting said cam disk and cam follower disk about a shaft for relative rotation; said disks being axially movable with respect to each other and being biased towards each other, said cam disk having alternately arranged annular dwells and depressions forming a circular cam track; means for varying the effective length of said dwells, said cam follower disk having a cam follower portion projecting axially into engagement with said cam track; a switch; a switch actuating member movable axially of said shaft to change the circuit controlling position of said switch; means operatively connecting said switch actuating member to one of said disks; and means for rotating one of said disks with respect to the other so that said disks are periodically moved apart axially against their bias to move said switch actuating member.

13. In a time switch; a cam disk and a cam follower disk; means for mounting said cam disk and cam follower disk about a shaft for relative rotation; said disks being axially movable with respect to each other and being biased towards each other; said cam disk having alternately arranged annular dwells and depressions forming a circular cam track; means for varying the effective length and number of said dwells; said cam follower disk having a cam follower portion projecting axially into engagement with said cam track; a switch; a switch actuating member movable axially of said shaft to change the circuit controlling position of said switch; means operatively connecting said switch actuating member to one of said disks; and means for rotating one of said disks with respect to the other so that said disks are periodically moved apart axially against their bias to move said switch actuating member.

14. In a time switch; a control panel; a cam

disk and a cam follower disk; means for mounting said cam disk and cam follower disk parallel to said control panel about a shaft for relative rotation with respect to each other; said disks being axially movable with respect to each other and being biased towards each other; said cam disk having alternately arranged annular dwells and depressions forming a circular cam track; means accessible from said control panel for varying the effective length and number of said dwells; said cam follower disk having a cam follower portion projecting axially into engagement with said cam track; a switch; a switch actuating member movable axially of said shaft to change the circuit controlling position of said switch; means operatively connecting said switch actuating member to one of said disks; and means for rotating one of said disks with respect to the other so that said disks are periodically moved apart axially against their bias to move said switch actuating member.

15. In a timer; a power operated rotatable element, said element also being axially movable, means to effect successive axial movements of said member comprising a pair of disks, said element having a part normally abutting said disks but being freed therefrom by rotation of said element, and a movable controlling member, the movement of which is controlled by the axial movements of said element.

16. In a timer, a power operated rotatable element, said element also being axially movable, means to effect successive axial movements of said member comprising a pair of disks, said element having a part normally abutting said disks but being freed therefrom by rotation of said element, and a controlling member the movement of which is controlled by the axial movements of said element, said part comprising a spring pressed member projecting toward the disks and the latter each having a slot therein to receive said member when registering therewith.

17. In a timer, a power operated rotatable element, said element also being axially movable, means to effect successive axial movements of said element comprising a pair of disks, said element having a part normally abutting said disks but being freed therefrom by rotation of said element, and a movable controlling member the movement of which is controlled by the axial movements of said element, said part comprising a spring pressed member projecting toward the disks, and the latter each having a slot therein to receive said member when registering therewith and said element being free for continued rotation relatively to said disks in any position of the latter.

18. In a timer, a power operated rotatable element, said element also being axially movable, means to effect successive axial movements of said member comprising a pair of disks, said element having a spring pressed part normally abutting said disks but before being freed therefrom by rotation of said element and a movable controlling member, the movement of which is controlled by axial movement of said element.

19. In a timer, a power operated rotatable element, said element also being axially movable, means to effect successive axial movements of said member comprising a pair of disks, said element having a part adapted to be engaged and released successively by said disks to permit axial movement of said element and a movable controlling member, the movement of which is controlled by axial movement of said element.

CERTIFICATE OF CORRECTION.

Patent No. 2,364,184.

December 5, 1944.

ALBERT E. BAAK.

It is hereby certified that error appears in the printed specification of the above numbered patent requiring correction as follows: Page 4, second column, line 64-65, strike out "68 are brought into engagement for a brief lay" and insert instead --66 are disengaged for deenergizing the relay--; and that the said Letters Patent should be read with this correction therein that the same may conform to the record of the case in the Patent Office.

Signed and sealed this 5th day of June, A. D. 1945.

Leslie Frazer

(Seal)

Acting Commissioner of Patents.
